UNITED STATES PATENT OFFICE.

HENRY A. WISE WOOD, OF NEW YORK, N. Y., ASSIGNOR TO WOOD & NATHAN COMPANY, OF NEW YORK, N. Y., A CORPORATION OF NEW YORK.

MOLD FOR SLUG-CASTING MACHINES.

1,082,059.

Specification of Letters Patent. Patented Dec. 23, 1913.

Application filed September 28, 1907. Serial No. 394,954.

To all whom it may concern:

Be it known that I, HENRY A. WISE WOOD, a citizen of the United States, residing at New York, in the county of New York and State of New York, have invented a new and useful Mold for Slug-Casting Machines, of which the following is a specification.

This invention relates to an improved form of mold for use in connection with type casting machines, especially those in which a full line of type faces is cast in one piece.

The principal object of the invention is to provide a construction whereby the line can be cast efficiently either in one piece or sections as desired.

As type-casting machines of this character are at present constructed, when it is desired to insert column-rules, recesses are cast in the lines at points where the rules are to be inserted. The difficulties in keeping the recesses in alinement, and in inserting and holding the rules constitute serious objections to this method. Furthermore, when it is necessary to make corrections, the rules have to be removed before the slug requiring correction may be taken out. Another way of operation when it is desired to insert column-rules is to cast printing faces representing sections of column rules on the faces of the slugs. This, however, has proven unsatisfactory, as these faces do not line up well in the form, and the printed line is interrupted and uneven. Also in casting a full line of type when an error has been made, it is necessary to reset and recast a complete line, which results in serious delays which are important in the class of work to which this machine is especially adapted.

The principal objects of this invention are to provide means for overcoming these objections. To provide a mold in which a line can be cast in sections of any desired size so as to improve the operation of machines of this character for ordinary work, and especially in connection with tabulated work where the lines are intersected by column rules, one or more dividing pieces are provided. These are so arranged that they may be inserted in the mold where it is desired to place the column-rules so that logotypes of the desired length may be produced. The dividing pieces may be of the same width as the column-rules, and in this

way the full capacity of the mold is maintained. It is to be understood moreover that the invention contemplates the casting of individual letters or other combinations of letters and logotypes, for general work preferably by inserting the dividing pieces between each two adjacent letters or at any desired points along the mold.

Although the invention is capable of general use, it is particularly advantageous when the machine is employed for tabulated work where the lines are generally long and errors frequently occur. As a matter of fact in practice the necessity for inserting and resetting a line for each error and removing the rules before a slug can be taken out makes line-casting machines impractical for this particular class of work.

Reference is to be had to the accompanying drawing which shows a preferred form of the invention, and in which—

Figure 1 is an elevation of a mold suitable for application to an ordinary line casting machine showing a preferred form of the present improvements. Fig. 2 is an end elevation of the same. Fig. 3 is a perspective view of a dividing piece adapted to be placed in the mold. Fig. 4 is a perspective view of a filling piece. Fig. 5 is a plan showing a special form of ejector which may be employed with this mold. Fig. 6 is an elevation of the same showing the mold in section, and Fig. 7 is a perspective view of one of the ejector blades.

The mold as usual in this type of machine comprises a body portion 10 designed to be fixed to a carrying disk, 9 and provided with guides 11 to hold the cap 12 in position. The liners 13 are arranged at the ends of the mold spaces in a well-known manner.

In order to provide for dividing up the mold space or cavity into a plurality of spaces of the same or different sizes so that the logotypes, single letters, or the like may be cast therein, a series of dividing pieces 14 are provided comprising plates 14 adapted to extend entirely across the mold space or cavity so as to cut off one side from the other and divide the mold into two or more independent mold spaces. In order to provide for holding these dividing pieces in position, each one is constructed with a body 15 and with a projection 16 of dove-tail or any other convenient shape. In the wall of the mold, preferably in the cap, is formed a space 17

extending along the mold and bounded on one side by the original mold space or cavity. This space 17 is of the same cross-section as the bodies 15, so that these bodies may rest 5 in this longitudinal space without projecting into the mold cavity, the surfaces 18 of these bodies thus constituting the surface of the mold space or cavity, and being located exactly in the plane in which the wall of 10 the old form of mold would be located. In a similar manner a groove 20 is cut at the rear of the space 17, and is of such shape, dove-tailed, in the present instance, as to hold the projection 16 in a similar way. 15 It will, of course, be obvious, that when these spacing pieces are placed in position it will be necessary to fill up the remainder of the space 17 and groove 20, and this is done by means of spacing blocks S each 20 having a body 22 fitting in the space 17 and a projection 23 fitting in the groove 20. This body and projection are of the same shape as the body 15 and the projection 16 respectively, and the bottom surfaces 24 of 25 the filling pieces constitute a portion of one wall of the mold. The dividing and filling pieces are made of a number of different lengths, preferably varying in accordance with the point-system or in any other 30 way according to the kind of work which is being done. In this way by rearranging them, slugs of any desired length can be produced in the mold.

The filling and dividing pieces are held 35 in position in the mold by any desired means; that shown, consisting of a clamping bar 25 set in a recess 26 in the front of the cap and held in position by screws or the like 27. The lower edge 28 of this clamping bar 40 engages in recesses 29 and 30 respectively on the front upper corners of the dividing and filling pieces. When it is desired to rearrange the dividing pieces, the clamping bar 25 is removed and the sections may then 45 readily be taken out and replaced in the desired way. The bodies 15 of the dividing pieces may conveniently be of a width equal to that of a plate 14 plus that of the smallest type matrix which is employed on the 50 machine in order to permit the production of single types by placing these dividing pieces side by side, the spacing pieces being employed when two or more types are to be formed integrally. Or dividing pieces 55 may be provided having bodies of any desired width. In order to eject these types, linotypes, or logotypes from the mold, a special form of ejector is preferably employed, indicated most clearly in Fig. 5. 60 This ejector is made up of a plurality of ejector blades 40, these blades being of varying widths to correspond with the widths of the spacing and filling pieces, and each one preferably being filled with small longitudinal V-shaped grooves 41 on one face

so that each blade section may always be so as to enter the spaces. The sections of the ejector blade are connected with the ejector mechanism 42 in such a manner that the several sections may be located with respect to each other in accordance with the mold spaces left in the mold by the dividing pieces. In order that this may be done, the ejector blades are each shown as provided with a transverse groove 43 on one face into 70 all of which fits a pivoted bar 49 mounted on the sliding member 42 of the ejector mechanism. A spring 45 is mounted on the member 42 to hold the bar 49 in operative position. A fixed guide 50 has ridges 51 to 75 enter the grooves 41 and guide the ejector blades properly into the mold spaces. The ends of the blades have slanting surfaces 60 extending nearly to the grooves 43 to assist in guiding the bar 49 into the grooves. 80

In operation the mold having been set up as above set forth and brought to position in the usual way, and the metal having been introduced into the mold as is well understood, when the mold is brought to ejecting 90 position, the ejecting slide 42 moves forward, and with it the several blades 40. These pass through the mold in the usual way and eject the several castings. As it is usual to have the mold located in vertical 95 position when the ejecting operation is performed, it will be seen that all the slugs will be forced from the mold, passing between trimming knives 46 and 47, when they move out of contact with these they fall one on 100 another, and rest on a ledge 48 formed on the trimming knife 46. From this position they are delivered in any desired way.

It will be seen that by the use of this invention single types, logotypes or linotypes 105 may be produced at will and especially in columns. This is of great advantage in ordinary work as when corrections have to be made, only a single slug has to be removed to make the correction and it is not necessary to reset and recast a complete line, the individual section only having to be recast. In some cases the section can be removed and individual type substituted for it.

The invention is particularly valuable in 115 connection with tabulated work where the lines are intersected by column-rules, as has been described above.

While I have illustrated and described a preferred form of the invention, I am aware 120 that many modifications may be made therein by any person skilled in the art without departing from the scope of the invention as expressed in the claims. Therefore, I do not wish to be limited to the particular 125 form shown, but

What I do claim is:—

1. A slug casting mold having a space along one wall thereof, dividing pieces having bodies fitting in said space, and spacing

pieces also fitting in said space, the dividing pieces having plates extending across the mold and having surfaces registering with the inner surfaces of the spacing pieces, 5 and the dividing and spacing pieces together filling all of said space.

2. In a slug casting mold, the combination of a body portion, a cap spaced from the body portion to provide a mold cavity, said 10 cap having a space along said mold cavity, and a dove-tailed groove at the rear of said space, dividing pieces, spacing pieces each having a body of the same shape as said space, and a dove-tailed projection fitting 15 said groove, said spacing pieces being located between the bodies of said dividing pieces, and serving to regulate their distance from each other.

3. In a slug casting mold, the combination 20 of a body portion adapted to be fixed to a disk or mold wheel, a cap spaced from the body portion to provide a mold cavity, and having a recess along the front thereof, said cap having a space along said mold cavity, 25 and a dove-tailed groove at the rear of said space, dividing pieces each having a projection fitting said groove, spacing pieces each having a dove-tailed projection fitting said groove, said spacing pieces being located between the bodies of said dividing 30 pieces and serving to regulate their distance from each other, and a clamping bar located in the recess in said cap and projecting in front of said dove-tailed projection for 35 clamping the spacing and dividing pieces in position on the cap.

4. In a slug casting mold, the combination of dividing pieces and spacing pieces therefor, the said dividing and spacing pieces 40 having bodies located in alinement along one side of the mold cavity and together constituting one wall thereof, said dividing pieces having relatively thin plates projecting from their bodies across the mold cavity.

45 5. In a slug casting mold, the combination of dividing pieces, spacing pieces therefor, said dividing and spacing pieces having bodies of the same cross section and being located in alinement along one side of the 50 mold cavity and together constituting one wall thereof and the dividing pieces having relatively thin plates projecting from their bodies across the mold, means for holding said bodies in alinement adjacent to the 55 mold cavity, and means for locking said dividing and spacing pieces in position.

6. In a slug casting mold, the combination of a body portion adapted to be fixed to a disk or mold wheel, a cap spaced from the 60 body portion to provide a mold cavity, and having a recess along the front thereof, said cap having a space along said mold cavity, and a dove-tailed groove at the rear of said space, dividing pieces each having a body 65 fitting said space, a projection fitting said

groove, and a plate extending across the mold space between the cap and body of the mold, spacing pieces each having a body of the same shape as said space, and a dove-tailed projection fitting said groove, said 70 spacing pieces being located between the bodies of said dividing pieces and serving to regulate their distance from each other, and a clamping bar located in the recess in said cap and projecting in front of said dove-tailed projection for clamping the 75 spacing and dividing pieces in position on the cap.

7. A dividing piece for a slug casting mold comprising a body adapted to form part of 80 the top of the mold, a dove-tailed projection on the top of said body, and a plate on the bottom of the body adapted to extend across the mold.

8. The combination with a mold adapted 85 to cast a plurality of separate types or slugs, of an ejector comprising a reciprocatory member and a plurality of ejector blades each having a groove, all of said grooves being arranged in transverse alinement, and 90 a holding bar transversely pivoted with respect to said reciprocating member and adapted to enter the grooves and hold the ejector blades in position.

9. In a device of the character described, 95 the combination of a mold arranged to cast a plurality of separate types or slugs, with an ejector comprising a movable member, a transverse holding bar connected to and movable therewith, and a plurality of 100 ejector blades each having a continuous transverse groove for receiving said bar at any point thereof to hold the said blades in any desired positions along the bar, whereby the motion of said movable member will 105 move all of said blades in any adjusted positions thereof along the bar.

10. The combination with a mold adapted 110 to cast a plurality of separate types or slugs, of an ejector comprising a reciprocating member, a bar pivotally mounted thereon, a spring for holding said bar, and a plurality of ejector blades each having a groove adapted to be engaged by said bar.

11. An ejector blade for a slug casting 115 mold, having a transverse groove near one end thereof, a slanting surface between the groove and the adjacent end, and a plurality of small V-shaped grooves on the face thereof.

12. The combination with a mold for casting slugs of a guide plate adjacent thereto having parallel ridges thereon, and an ejector blade having corresponding grooves adapted to be guided into the mold by said ridges.

13. A linotype mold comprising cap and body portions with an intermediate longitudinal mold slot open at the front and rear, partitions having bodies and projecting plates located in the mold and slidably inde- 130

1,082,059

pendently lengthwise of the mold, and intermediate interchangeable filling pieces adapted for insertion between the partitions, and having bodies of the same size and shape 5 in cross section as the bodies of the partitions and registering therewith.

In testimony whereof I have hereunto set

my hand, in the presence of two subscribing witnesses.
